UNITED STATES PATENT OFFICE.

OSCAR WIEDERHOLD, OF EAST ORANGE, NEW JERSEY.

MOUNTING FOR INCANDESCENT GAS-MANTLES.

SPECIFICATION forming part of Letters Patent No. 687,360, dated November 26, 1901.

Application filed August 29, 1900. Serial No. 28,404. (No model.)

To all whom it may concern:

Be it known that I, OSCAR WIEDERHOLD, a citizen of the United States, residing at East Orange, Essex county, State of New Jersey, have invented certain new and useful Improvements in Mountings for Incandescent Gas-Mantles, of which the following is a specification.

My invention relates to mountings for incandescent gas-mantles, and has for its object to produce a structure which may be utilized for safely transporting a mantle and for mounting the same in the gas-fixture.

To this end my invention consists in the special matters hereinafter pointed out in the claim.

My invention is illustrated by way of example in the accompanying drawings, which show one form of my invention.

20 In the drawings, Figure 1 is a central vertical sectional view of the device. Fig. 2 is a horizontal section on line 2-2 of Fig. 1. Fig. 3 is a cover carrying the plug, and Fig. 4 is a side view of the mantle-supporting cap.

25 In the various figures, in which like parts are indicated by similar reference-letters, *a* is the mantle-supporting cap, which is shown as cut in order to provide integral inwardly-projecting spring-tongues *b*, which are adapted to springily engage the sides of the gas-fixture, burner-tube, or mixing-chamber, or the sides of the block *c*, mounted upon the cover *d* of a box *b'* and adapted to be engaged by the spring-tongues *b*. The cap has a flaring or 35 concaved portion *a'*, and to this portion the ends of the tongues *b* are attached, so that the lower ends of the tongues are bent and flare outwardly, thereby increasing the resiliency

of the tongues. The cap is likewise provided with a split tube *e*. The mantle-supporting wire *f* is inserted in the said split tube and being firmly gripped by the said split tube will be adjustable up and down therein and will be held by the said tube in any of its adjusted positions. The mantle *g* is suspended 45 from the mantle-wire. A packing-box or cylindrical casing *h* is adapted to surround the mantle *g* and the mounting and fits into the covers *d* and *i*. The mantle may thus be efficiently transported, and in order to use the 50 same it is merely necessary to remove the cap *a*, carrying the mantle-wire and mantle, and to mount the said cap upon the burner-tube, it being understood that the springs or spring-tongues *b* project inward and are adapted to 55 engage the sides of the burner-tube or mixing-chamber in order to support the mantle on the lamp.

It is to be observed that the structure described herein is an improvement upon the 60 structure shown and described in certain United States Letters Patent to Theodore Mulch, No. 593,231, dated November 9, 1897.

Having described my invention, what I claim, and desire to secure by Letters Patent, 65 is—

A mantle-supporting device comprising a collar provided with a mantle-support and formed with a flaring portion, and with integral tongues the lower ends of which are connected with the flaring portion of the collar and are themselves bent and flare outwardly. 70

OSCAR WIEDERHOLD.
